UNITED STATES PATENT OFFICE.

GEORGE W. BLAIR, OF MISHAWAKA, INDIANA, ASSIGNOR TO MISHAWAKA RUBBER AND WOOLEN MANUFACTURING COMPANY, OF MISHAWAKA, INDIANA, A CORPORATION OF INDIANA.

SHOE-SOLE CONSTRUCTION.

Application filed November 6, 1925. Serial No. 67,212.

My invention relates to the construction of soles of shoes and the like and has reference more particularly to the manner of securing the outer sole to the bottom structure 5 of the shoe.

It has been found desirable in the manufacture of shoes to use outer soles of composition containing rubber, this type of sole being particularly advantageous in work 10 shoes, boys' shoes and in other cases where the shoes are subjected to hard usage or used largely out of doors or in wet places. Soles of this character are not only extremely durable and waterproof but are more flexible 15 than leather soles and avoid the stiffness and discomfort occasioned particularly in heavy shoes when soles of leather are employed. However, a serious objection has been encountered in the use of the composition 20 soles due to the tendency of such soles to stretch under constant usage particularly when exposed to oil or oily substances and this stretching causes the outer sole to bulge 25 and pull away from the bottom structure of the shoe.

The principal objects of my invention are to minimize the stretching of outer soles of composition material; to hold the outer sole at various points throughout its area securely 30 to the superposed portion of the sole structure; to prevent bulging of the composition sole; to securely and permanently unite middle portions of the outer sole with the superposed layer or layers of the assembled sole; to provide a convenient and inexpensive 35 method and means for reinforcing the outer sole against stretching and bulging; and in general to improve and increase the durability of composition soles.

On the drawings Fig. 1 is a side view of a 40 shoe embodying my improvements, with a portion broken away to disclose details of construction.

Fig. 2, a bottom view of the forward portion 45 of the sole with a portion of the outer sole broken away; and

Fig. 3, a sectional view along the reinforcing line of stitches, taken substantially along the line 3—3 of Fig. 2.

Referring to the drawings I have shown 50 my invention applied to a shoe of an ordinary type although it is to be understood that my improvements may be used in connection with other types of footwear. The

reference numeral 1 indicates the upper of 55 the shoe as a whole which in the present case is provided with a lining 2. 3 is the inner sole over which the lower edge of the upper 1 and lining 2 is lasted in the usual manner and 4 is a middle sole which projects beyond 60 the inturned lower edge of the upper 1 and is secured in place by the marginal line of stitches 5 which are passed through the middle sole 4, the inturned edge of the upper and the marginal portion of the inner sole 3, and serve to secure the inturned lower edge of the upper firmly between the marginal portions of the insole 3 and the middle sole 4.

The inturned edge of the upper 1 forms a 70 raised edge around the under side of the inner sole 3 and the cavity or space embraced thereby is filled in, preparatory to the application of the middle sole 4, by a filling 6 of cork fragments or other suitable material. 75 The filling 6 or layer of cork fragments is cemented on to the outer side of the inner sole 3 and the middle sole 4 is cemented to the outer surface of the filling 6 or layer of cork fragments. 80

The outer sole 7 which may be of any suitable composition such as it is now a common practice to use is laid against the outer surface of the middle sole 4 and preferably cemented thereto after which a line of 85 stitches 8 is applied around the edge thereof and through the edge of the middle sole 4 for the purpose of securing the outer sole 7 to the shoe. In the preferred construction a line of lock stitches 9 is then applied 90 through the marginal portions of the inner middle and outer soles 3, 4 and 7 respectively and through the inturned edge of the upper 1 so as to unite the layers of material composing the entire sole and further secure the sole to the upper, this line of stitches being composed of upper and lower threads which are looped together well within the combined sole so that the connection between the upper and lower threads is thoroughly protected against wear or separation. 95 100

In shoes and footwear wherein the outer sole is composed of a composition containing rubber it has been found that sometimes when subjected to hard usage, and particularly when the shoes are worn in places where they are subjected to oil or oily substances, the composition sole has a tendency 105

2
to stretch and pull away from the middle sole or superposed sole structure and causes an undesirable bulging of the outer sole. In order to avoid the tendency of the composition outer sole to pull apart from the other sole structure and to prevent the stretching or bulging of this outer sole I provide one or more lines of stitches to connect the middle portion of the outer sole 7 with the other 10 layers composing the sole so that the center portion of the outer sole is firmly secured to the other layers of the entire sole and held thereby against stretching and bulging. The stitches may be arranged in any convenient 15 manner in somewhat concentric and elliptically formed lines as shown at 10 and 11, and the stitches are preferably lock stitches with the connection between the upper and lower threads embodied well 20 within the sole so that the interengaged portions of the threads are thoroughly protected against injury in using the shoe. The lines of stitches may be arranged otherwise than as shown in the drawing either by employing 25 transverse, longitudinal or otherwise arranged lines of stitches which serve to reinforce the center part of the sole and are sufficiently close to the outer rows of stitches to prevent any material loosening up or 30 bulging of the outer sole 7.

In practice the outer sole 7 is usually made with a fabric covering 12 firmly secured to the upper surface by vulcanizing or otherwise which serves to materially avoid 35 stretching or distortion of the outer sole 7.

The middle sole may be of any desired 40 construction, but is preferably adapted to resist stretching. In the present case this middle sole is a laminated structure comprising a middle layer 13 of leather or fibrous material having outer layers 14 of composition vulcanized or otherwise firmly secured thereto.

With this construction not only is the 45 bulging or stretching of the outer sole prevented but the various layers composing the entire sole are firmly bonded together so that the adhesion due to the cementing together of the layers of the sole is maintained and 50 moreover slipping action or relative movement between the layers of the sole which oftentimes occurs in walking or bending the sole of the shoe and which imposes excessive strain on the fastenings, is obviated and

a stronger, more substantial and durable 55 shoe results.

In view of the fact that the stitches 10 and 11 are lock stitches having the interengaged loops of the upper and lower threads embedded in the sole, there is sufficient frictional engagement of the threads with the outer sole so that in the event that the exposed portions of the threads are worn down and separated the connection of the outer sole is still maintained by the engagement of the remaining portions of the threads with the outer sole. After the center stitching of the shoe is completed a sock liner 15 is preferably inserted and cemented in place so as to cover the exposed upper ends of the stitches and afford a smooth comfortable surface for supporting the foot.

While I have shown and described my invention in a preferred form, I am aware that various changes and modifications may be made without departing from the principles of my invention the scope of which is to be determined by the appended claims.

I claim:

1. In a shoe, the combination of an inner sole, an outer sole of rubber composition and an intermediate sole, separate stitches connecting the inner and outer soles to said intermediate sole, a continuous line of stitches around the toe, ball and shank portions and extending through and connecting the inner and outer soles to said intermediate sole, and stitches distributed substantially throughout the area of and interlocking the tread portion of the outer sole with said inner and intermediate soles.

2. In a shoe, the combination of an inner sole, an outer sole of rubber composition, an intermediate sole, separate stitches connecting the inner and outer soles to said intermediate sole, a continuous line of stitches around the toe, ball and shank portions and extending through and connecting the inner and outer soles to said intermediate sole, and lock stitches distributed substantially throughout the area of and interlocking the tread portion of the outer sole with said inner and intermediate soles, the inter-engaging portions of the upper and lower threads of the lock stitch being located within the combination sole.

GEORGE W. BLAIR.
